Patented Jan. 3, 1922.

WITNESS:

Thos. W. Riley

TIT. 2.

Diagram of a valve assembly labeled 'FIG. 5'. The assembly consists of a central vertical stem with a handle at the top. A horizontal pipe connects the stem to a circular base. The base has two diagonal hatching patterns on its left side, labeled '52' and '53' respectively. The top of the stem has a rectangular slot, labeled '54'.

TYPEWRITER RIBBON VIBRATOR.

1,402,264.

Specification of Letters Patent.

Patented Jan. 3, 1922.

Application filed March 6, 1919. Serial No. 280,948.

To all whom it may concern:

Be it known that I, CHARLES SPIRO, citizen of the United States, residing at New York, in the county of New York and State 5 of New York, have invented certain new and useful Improvements in Typewriter Ribbon Vibrators, of which the following is a specification.

This invention relates to a typewriter ribbon vibrating mechanism, and particularly to a construction adapted to vibrate the ribbon in varied paths, as required in the use of a polychrome ribbon for printing in different colors.

15 The invention has for an object to provide a novel and improved construction for varying the path of vibration of the ribbon, and comprises a vibrator lever operatively connected to an actuating lever which is oscillated by a connecting member upon a universal bail having its point of connection with the actuating lever shiftable relative to the fulcrum thereof.

25 A further object of the invention is to provide an improved construction of actuating lever and shiftable connecting link, particularly adapted for use in connection with a reciprocating typebar actuated universal bail.

30 Another object of the invention is to present a novel construction of connection and mounting for the vibrator lever and connection therefrom to the actuating lever by which the former may be vertically shifted 35 with the platen without affecting the operation of the parts nor the vibration of the ribbon in different paths of travel.

Other and further objects and advantages of the invention will be hereinafter defined 40 and the novel features thereof defined by the appended claims.

In the drawing—

Figure 1 is a central vertical section showing the invention applied to a typewriting 45 mechanism;

Figure 2 is a detail perspective of the ribbon vibrating members, and Figure 3 is a detail section of the vibrator connection.

Like numerals refer to like parts in the 50 several figures of the drawing.

The numeral 10 designates the frame of a typewriter, which may be of any desired construction or configuration, and has mounted at the rear thereof the shifting

plate 11 and posts 12 depending therefrom 55 and passing through guides 13 upon the frame. These posts are reciprocated by the usual shift key levers 14 in the ordinary manner. The plate 11 carries the typewriter carriage 15, which may be of any 60 preferred form, and is provided with the platen 16 adapted to be shifted vertically with the carriage for upper or lower case printing.

The frame is also provided with the usual 65 sector 17 upon which the typebars 18 are pivoted, and these typebars are actuated by the ordinary lever connections for that purpose. The sector also has mounted thereon the usual universal bail or bar 19 disposed 70 to be operated in one direction by the shoulder 20 upon the typebar.

The vibrator bracket 21 is secured to the shifting plate 11 in any desired manner, and has the horizontal portion 22 extending 75 rearward therefrom. The end 23 of this portion is extended downward at an angle thereto and carries the pivoting arm 24 lying beneath the portion 22 and in a parallel horizontal plane.

80 The vibrator lever 25 is pivoted at 26 to this arm and the forwardly extending member 27 thereof has pivotally mounted at its outer end 28 the ribbon arm or holder 29 which supports the ribbon 30 in the usual 85 manner. The arm 24 is formed with a supporting flange or lug 31 extending beneath the member 27 so as to lift the lever and ribbon when the carriage and platen are vertically shifted for upper case work.

90 The vertical arm 32 of the vibrator lever is provided with a lateral pin 33 which extends through a slotted vertical extension 34 at the free end of the actuating lever 35. This lever is disposed in a horizontal plane 95 at the rear of the bail 19 and is mounted by a pivot 36 upon a bracket 37 secured to the side of the typewriter frame. The pivoted end of the actuating lever is formed with a vertical end wall 38 having a lateral pivoting flange 39 at its upper end through which the pivot 36 extends. This construction provides an elongated support for the pivot of the actuating lever which insures 100 easy and accurate operation thereof when the vibrator lever is in either of its shifted positions.

For the purpose of varying the length of

travel or throw of the actuating lever and the consequent path of vibration of the ribbon, the lever is provided with an elongated slot 40 extending longitudinally thereof and 5 adapted to receive a pin or screw 41 carried by the inner end of the connecting link member 42. The opposite end of this link is pivotally mounted at 43 upon the universal bail 19 in any desired manner. The 10 slot 40 is preferably formed with a segmental wall and if desired the opposite wall thereof may be formed with an open portion extending between the end tongues 45. This provides means by which the link may 15 be shifted into a position where it will not actuate the lever, for instance when it is desired to perform stencil cutting work.

The link is preferably disposed beneath the lever 35 and the head of the connecting 20 screw 41 retains the parts in proper shiftable position. In order to position the opposite end of the link in alignment with the lever it is desirable to pivot the same upon a bracket 46 extending upward from the 25 universal bail and parallel thereto. This permits the link to operate in a horizontal plane parallel with the plane of the actuating lever.

The link may be shifted by any desired 30 connections, for instance the rod 47 pivoted thereto and extending to the bell-crank lever 48 pivoted at 44 upon the bracket 37. From the opposite arm of this lever an operating rod 49 extends to a switch lever 50 pivoted 35 upon the typewriter frame adjacent the key board thereof. The travel of the lever 50 is limited by stops 51 at each side thereof which also indicates the position and color of the ribbon path in use.

40 It will be observed that the vibrator lever and the actuating lever oscillate in planes at substantially a right angle to each other, and if the connecting pin from the former were straight at its contact edges the slot in the latter would have to be wider than the diameter of said pin in order to transmit motion at all points in the different arcs of travel of said parts. This would result in a loose and undesirable connection which also renders impossible an accurate vibration of the 45 ribbon, especially for the upper or red color path, as the shifting of the universal bail by which the ribbon is vibrated occurs near the end of the typebar travel. It is therefore necessary that a constant close contact be 50 maintained between the actuating and vibrator levers so that no lost motion shall occur, and to secure this essential function the pin 33 from the vibrator lever is provided 55 with a curved or ball shaped contact face 52 disposed to maintain constant contact with the vertical walls 53 of the slot in the extension 54 from the actuating lever. This construction greatly reduces the frictional contact 60 between the pin and the slot walls while

effecting a positive shifting for writing on either color path, and also prevents the partial shifting frequently due to loose connections by which both colors show at a single impression. The ball shown is a desirable 70 form for securing these results, but other arrangements of the contacting parts may be effected to secure a close contacting relation between the actuating and vibrator levers in their several positions due to their arcs of 75 travel or their shifted relation. This connection is particularly adapted for use when the actuating lever is mounted to oscillate in a different plane from the vibrator lever, which causes the arcs of travel to diverge, as 80 there is only a limited travel of the universal bail the motion of which must be fully transmitted to the ribbon especially during the period of its longest degree of vibration.

In the operation of the invention it will be 85 seen that when the connecting link is shifted to the end of the slot in the actuating lever nearest its pivot the greatest extent of movement will be imparted thereto and to the ribbon vibrator so as to print upon the lower 90 color path thereof. This arrangement of the parts is shown in Figure 2 of the drawing and when the link is shifted to the opposite end of the slot the actuating lever is given its shortest movement and the upper 95 color path of the ribbon vibrated at the printing point. With the link in an intermediate position or opposite the opening in the slot no motion is imparted to the actuating lever and consequently the ribbon 100 vibrator remains at rest as when the machine is used for stencil cutting purposes. The construction and arrangement of the actuating lever disposed between the universal bail connection and the vibrator lever particularly adapts the invention for use with a 105 typebar actuated reciprocating bail and provides a simple, efficient and economically constructed appliance for vibrating a bichrome ribbon in varied paths. The long 110 bearing at the pivotal end of the actuating lever prevents play or wabbling thereof and insures stability necessary for an accurate movement of this lever in its relation with the connected shiftable vibrator lever. The 115 ribbon holder and vibrator are also mounted to be shifted with the platen for upper or lower case printing and without affecting its operative relation with the actuating lever.

While the details of the construction and 120 mounting of the several parts of the invention have been specifically shown and described, still the invention is not confined thereto as defined by the following claims.

What I claim is:—

125 1. In a ribbon vibrator, an actuating lever, a vibrator lever pivoted independently thereof to oscillate in a plane at an angle to the actuating lever and connected thereto, a typebar actuated universal bail having a 130

- part movable in the plane of the actuating lever, and connecting means extending from said bail to said actuating lever.
2. In a ribbon vibrator, an actuating lever, a vertically disposed vibrator lever mounted upon a relatively fixed part to oscillate in a plane at an angle to the actuating lever and directly connected thereto at a free end thereof, a universal bail, and a connecting link mounted thereon and adjustable longitudinally of the actuating lever relative to the pivot thereof.
3. In a ribbon vibrator, a vibrator lever, an actuating lever directly connected therewith, a universal bail, a connecting link mounted thereon and adjustable longitudinally of the actuating lever relative to the pivot thereof, a switch lever, a rod extending therefrom to said link, and means for operating said switch lever.
4. In a ribbon vibrator, a vibrator lever, a longitudinally slotted actuating lever directly connected therewith, a typebar actuated reciprocating universal bail, and a connecting member pivotally mounted thereon and adjustable in the slot of said actuating lever.
5. In a ribbon vibrator, a vibrator lever, an actuating lever pivoted at one end, means at the opposite end thereof for connection with said vibrator lever to permit relative vertical movement, a reciprocating universal bail, and a connecting member pivotally mounted thereon and adjustable upon the actuating lever relative to the pivot thereof.
6. In a ribbon vibrator, a vertically disposed vibrator lever, a horizontally disposed actuating lever connected thereto at one end, a reciprocating universal bail, and a connecting member pivotally mounted thereon and adjustable upon the actuating lever relative to its pivot.
7. In a ribbon vibrator, a vertically disposed vibrator lever, a horizontally disposed actuating lever having a vertical extension at one end connected thereto, a reciprocating bail, and a connecting member pivotally mounted thereon and adjustable upon the actuating lever relative to its pivot.
8. In a ribbon vibrator, a vibrator lever provided with a lateral connecting pin, an actuating lever pivoted at one end and provided with a longitudinally extending segmental slot, a connecting member at one end of the actuating lever to engage said pin, a universal bail, and a link pivoted thereon and mounted to be adjustable in the slot of the actuating lever.
9. In a ribbon vibrator, an angular vibrator lever provided with a lateral connecting pin, an actuating lever pivoted at one end and provided with a longitudinally extending segmental slot, an angular slotted member at the opposite end of the actuating lever to engage said pin, a universal bail,
- a link pivoted thereon and mounted to be adjustable in the slot of the actuating lever, and means for shifting said link.
10. In a typewriter, a frame, a vertically shifting carriage mechanism provided with a platen, a ribbon holder arranged for movement toward and from the printing point on said platen, a vibrator lever for said holder mounted to shift with said carriage mechanism, an actuating lever having a slotted connection with the vibrator lever to permit relative shifting thereof, a universal bail, and a connection therefrom shiftable toward and from the pivot of the actuating lever.
11. In a typewriter, a frame, a vertically shifting carriage mechanism provided with a platen, a ribbon holder arranged for movement relative to said platen, a vibrator lever for said holder, a bracket mounted to shift with said mechanism and having means to support said lever during the shifting action, a lateral projection from said vibrator lever, an actuating lever pivoted at one end and having at its opposite end a slotted member to receive said projection, a universal bail, and a connection pivoted thereon and shiftable upon the actuating lever relative to the pivot thereof.
12. In a typewriter, a frame, a vertically shifting carriage mechanism provided with a platen, a bracket mounted to shift with said mechanism and having a forwardly extending pivoting arm, a ribbon holder, a vibrating lever therefor pivoted upon said arm, a member carried by said arm to contract with the under face of said lever, an actuating lever connected to said vibrating lever, a universal bail, and a connection therefrom to said actuating lever.
13. In a ribbon vibrator, an actuating lever having a vertical wall at one end provided with a pivoting flange and a vertical slotted extension at the opposite end thereof, a pivoting bracket for one end of said lever, a vibrator lever connected to said slotted extension, a universal bail, and a connection therefrom to the actuating lever.
14. In a ribbon vibrator, an actuating lever pivoted at one end and provided with a longitudinally extending slot having a segmental wall, a universal bail, a connection therefrom shiftable along said wall, and a vibrator lever connected with the free end of said actuating lever.
15. In a ribbon vibrator, a universal bail, a horizontally disposed actuating lever having a case shift extension at one end, a shiftable connection between said bail and lever for varying the travel of the latter, and a vertically disposed vibrator lever pivoted independently of the actuating lever and directly connected to case shift upon said extension therefrom.
16. In a ribbon vibrator, a case shifted pivoted vibrator lever, a non-case shifted

1 actuating lever mounted to oscillate in a plane at an angle thereto, a universal bail, a connection therefrom to operate said actuating lever, and a universal joint connection between the vibrator and actuating levers constructed and arranged to maintain constant close contact between the same during their vibrating and case shifting operations.

10 17. In a ribbon vibrator, a case shifted pivoted vibrator lever, a non-case shifted actuating lever mounted to oscillate in a plane at an angle thereto, a universal bail, a connection therefrom to operate said actuating lever, and a connection between the vibrator and actuating levers having a curved contact face disposed to maintain constant contact between the engaging surfaces of said levers during their vibrating and case shifting operations.

18. In a ribbon vibrator, a case shifted pivoted vibrator lever, a non-case shifted actuating lever mounted to oscillate in a

plane at an angle thereto, and a pin and slot connection between said levers constructed and arranged to maintain constant close contact between the same during their vibrating and case shifting operations.

19. In a ribbon vibrator, a case-shifted pivoted vibrator lever, a non-case-shifted actuating lever mounted to oscillate in a plane at an angle thereto, a slotted member carried by one of said levers, and a ball member carried by the other lever and disposed in said slot.

20. In a ribbon vibrator, a vibrator lever disposed in a plane at an angle to the axis of a platen, an actuating lever therefor disposed to oscillate in a plane parallel to said axis, and a pin extended from one lever and provided with a spherical head closely seated in an aperture in the other lever.

In testimony whereof I affix my signature.

CHARLES SPIRO.
